UNITED STATES PATENT OFFICE.

PATRICK J. MENAHAN, OF BROOKLYN, NEW YORK.

PATTERN-PLATE FOR FOLDING AND MARKING GARMENT-SECTIONS.

SPECIFICATION forming part of Letters Patent No. 731,413, dated June 16, 1903.

Application filed December 3, 1900. Renewed May 25, 1903. Serial No. 158,646. (No model.)

To all whom it may concern:

Be it known that I, PATRICK J. MENAHAN, a citizen of the United States, residing in the borough of Brooklyn, in the city and State of New York, have invented a certain new and useful Improvement in Pattern - Plates for Folding and Marking Garment-Sections; and I do hereby declare that the following is a full, clear, and exact description thereof as applied to the manufacture of corsets.

The invention treats two pieces at a time and prepares them rapidly and very perfectly without requiring highly-skilled labor. The apparatus required is relatively inexpensive and very simple and durable. The treatment is applicable to the manufacture of various garments where any considerable number are to be produced alike.

I will first describe the invention as applied to the preparation of one pair of pieces for a pair of corsets.

In the manufacture of corsets there are separately-made triangular pieces of muslin or other fabric, technically termed "gores," applied in each side. These gores properly treated at their edges are set in narrower V-shaped notches in the main body of the corset, secured by two parallel lines of stitches near each edge, and increase the size of the garment at those points. For each gore there is a counterpart of the same size and a reversely-corresponding form to apply in the opposite half of the corset. Blanks for gores of the proper outline and so much larger than the completed gores as will allow about the ordinary margin for the infold or seam fold are previously cut from the fabric. This cutting is an old and well-known step. It may be effected by any ordinary or suitable means, as extending the material smoothly in many layers—say forty-eight—and cutting through the whole at one operation by a knife moved by hand around a templet of the required form and size. When very many are required, these blanks may be produced by forcibly depressing a cutting-die of the required size and form. The blanks for several gores are afterward treated in pairs by holding, marking, and folding by the aid of my apparatus in the manner fully described below. I shall refer to the broad end of the gore as the "front" during this treatment.

The following is a description of what I consider the best means of carrying out the invention.

The accompanying drawings form a part of this specification.

Figure 1 is a plan view of the lower plate and block. The strong lines indicate the outline of the bottom or main plate, the heavy dotted lines within two of its edges indicate the outline of the block on which it is carried, and light dotted lines outside of the figure indicate the edges of the blanks as cut and applied on the plate before being treated. Fig. 2 is a corresponding view of the intermediate plate. Fig. 3 is a corresponding view of the top plate. Fig. 4 is a transverse section through the block and main plate on the line 4-4 in Fig. 1. Fig. 5 is a corresponding section showing the pair of blanks in position to be treated. Fig. 6 is a corresponding section with the second plate, the intermediate plate, applied and held in position for marking by its aid the inner-seam line on both the blanks. Fig. 7 is a corresponding section with the third plate, the top plate, applied. Fig. 8 is a corresponding section with the overhanging edges of the blank deflected apart or partially folded after they have been wetted. Fig. 9 is a corresponding section showing the whole after the infolds have been properly folded, the upper one folded upward and the lower one folded downward, the corresponding plate being used as a "former" to determine the exact places of the folded lines. Fig. 10 is a corresponding section showing the same after the upper or top plate has been drawn forward and lifted off. Fig. 11 is a corresponding section showing the pair of gores after the treatment has been completed, but before they are separated from each other. Figs. 12 and 13 are corresponding sections showing the completely-prepared gores separated and ready to be applied in the corset. Fig. 14 is a face view of a main plate adapted for treating those front portions of the main body of the corset sometimes termed the "clasp-pieces" or "bust-pieces." Fig. 15 is a face view with a pair of blanks and the corresponding top plate applied. Fig. 16 is a cross-section on the line 3-3 in Fig. 14. Fig. 17 is a face view of a main plate adapted for treating the larger portions of the main body,

usually termed the "back-pieces." Fig. 18 is a face view with a pair of blanks and a top plate applied. Fig. 19 is a cross-section on the line 6 6 in Fig. 17.

5 Similar letters of reference indicate like parts in all the figures where they appear.

The thickness of the several plates is exaggerated to show the construction and effect plainly.

10 A is the main plate of metal, having the form and size of a completed gore.

A' represents pins, shown as permanently set in the plate A in erect positions near each end.

15 A² is a block of wood or other suitable material, smaller than the plate A, upon which the plate A is firmly and permanently secured.

B is an intermediate plate of metal having the form of the plate A, but smaller. It is 20 provided with close-fitting holes b, which match on two of the pins A' and maintain it in the true position laterally while in use.

C is a top plate of metal coinciding in form and dimensions with the plate A and adapted 25 to be applied thereon, on which is preferably riveted a handle C', by which it may be conveniently manipulated. It is provided with three slots c, extending in parallel directions, two closed and one open.

30 The several pieces of fabric cut to constitute the proper blanks are marked M M'. Each is of such size and form as to produce the required finished gore corresponding to the plates A and C with sufficient margins

35 M' along the edges to fold and form the seams by which this complete piece shall be joined to the other parts of the corset.

To operate the invention, the plates C and B are temporarily removed, a pair of blanks

40 M M' in the extended condition placed on the main plate A, with the pins A' extending up through the fabrics, so as to hold the two pieces of fabric, reliably against lateral displacement, and the intermediate plate B is

45 applied with its holes b matched on two of the pins A'. Marks are next made by any suitable implement, as the edge of a dull knife pressed upon the pair of fabrics M and moved along the two edges B' B² of the plate

50 B successively. This treatment produces indented lines m along those edges on both the blanks, which indicate the proper lines

55 which the first row of stitching will finally follow. Next the top plate C is applied, receiving the several pins A', each so held that the pins are each in the front end of its corresponding slot c. Next the projecting edges of the blanks M are wetted by a sponge or otherwise and are separated, the lower one

60 folded downward under the main plate A and the upper one folded upward upon the upper face of the plate C. The block A², which supports the plate A, is sufficiently smaller to allow the margin for the seam to be thus folded

65 smoothly under. It is shown as of the same form; but this is not important, as it performs no function in directly shaping. Now

the preparation of this pair of gores is completed; but their removal requires some care. The seam-margin of the upper blank being 7c folded inward over the adjacent portion of the upper plate C would be disturbed by a direct lifting movement of such plate. This is not a serious difficulty but it is well to avoid it. The facts that the parts being prepared are tapering gores and that the apertures c are slots instead of round holes become important by making it practicable to avoid disturbing the folds of the upper blank. The plate C, operated by the attendant by the 80 aid of its handle C', is first drawn forward to the extent permitted by the slots c. After this movement is made the way is clear, and it can then be directly lifted and removed. The plate B is next removed and both blanks 85 M M' M M' are lifted off together and laid on the bench or on the pile of previously-prepared gores, taking care when there is much piling of these completely-formed gores that the folded seam-margins M' be not flattened 90 out, but, on the contrary, be kept folded, so that they shall be held folded down still flatter as the weight of succeeding instalments is applied above. I have determined by experiments that it is easy to mark the line for the 95 parallel seam on the two blanks in the manner described, as they are held by my plates A and B, and that the marking shall not only be clearly shown on the uppermost of the pair of gores sufficiently to guide the needle-woman in putting in the line of stitches to 100 secure that in place on its proper half of the corset, but the mark will also be shown with nearly equal distinctness on the corresponding blank which lies below and which being 105 a counterpart of the upper is properly shaped and marked to serve in a corresponding reversed position on the opposite half of the corset. Thus the folding and the marking properly fit each of the two gores M M to serve 110 on their respective sides.

The sewing may be as usual. The first line of stitches applied along the mark m secures the gore to the body of the corset, (not shown,) leaving the folded seam-margin M' nearly or 115 quite untouched. The second line of stitches is applied through the folded part M', as well as through the body M, all as has long been practiced.

My invention gives great perfection with 120 little labor and may be worked by relatively unskilled operators.

Modifications may be made without departing from the principle or sacrificing the advantages of the invention.

125 When a fabric is used having a right and a wrong side, as is the case with satins and with many other kinds of goods, the layers of fabric must be reversely arranged. Such piling, one with its right face upward and the next with its right face downward, may be done either in arranging the goods before the blanks are cut or after they are cut and when they are being applied on the main plate A.

I can adapt the invention to the production of other pieces and for other garments than corsets. For treating a pair of gores, as in Figs. 1 to 13, inclusive, instead of the three pins A', I can make two suffice, or I can use a greater number than three. Only one at each end can be allowed in treating the narrow gores, which extend up and down obliquely near the bottom of the front of each side of the corset.

In Figs. 1 to 13 two edges are treated and one, the front edge, is left untouched. There may be any form of the support along the edge or edges not to be treated. The edge of the support may be flush with the edge of the main plate or may extend out beyond it. The edge or edges to be folded may be long apertures within or partially within the border of the piece, taking care to provide suitable plates and also suitable supports to allow space for folding under along such interior lines.

Figs. 14, 15, and 16 show a portion of my invention applied for treating blanks for bust pieces of corsets. This work requires no intermediate plate. G is the main plate, G' the pins, and G² the support. The plate may, as in the other forms, be sheet-iron about No. 30, and the support may be pine lumber sufficiently smaller along the proper edges to allow the lower blank to be folded downward. They may, as in the other form, be secured together by nails, having their heads sunk flush. There are three seam-margins or infolds P' of the properly-shaped blanks which are to be treated. The blanks are set in pairs properly matched on the main plate G, held laterally by the pins G', covered by the top plate H, which receives the pins G' in close-fitting holes h, and the projecting margins P', each of the proper breadth to form the required infold, are wetted and are folded, the lowermost downward and the uppermost upward. When completed, the pair of bust pieces are liberated in the obvious manner after lifting off the top plate. In the preparation of these pieces there is not so much advantage in moving the top plate before lifting it as in the regularly-tapered gores first described; but in this modification the holes h may, if preferred, be elongated to accommodate any direct bodily movement of the top plate or any torsional movement or the two movements combined, which may be found desirable.

Figs. 17, 18, and 19 show a portion of my invention applied for treating blanks for what are termed the "back-pieces" of corsets. This construction does not require any intermediate plate. J is the main plate, J' the pins, and J² the block or support. K is the top plate, k the holes which receive the pins J', and k' k² are closed slots. There are in this construction of the apparatus four edges J³ and K³ of the plates J and K, respectively, along which the blanks T are to be folded.

The blanks extend each beyond these edges of the plates on the same principle as in the other forms—just enough to afford material for proper infolds. These edges T' are all 70 along interior lines, two being along the two edges of a deep narrow notch or open slit j and the other two along the two sides of another nearly-similar deep notch j', both notches extending upward from the lower edge of the 75 plates. The blanks T T' are, as before, treated in pairs, the lower blank having its four seam-margins or infolds T' folded downward and the upper blank having its four corresponding seam-margins folded upward. An 80 other feature of importance is introduced in this modification. A tapering plait T² is to extend up from one of the deep notches j' to the top of the back piece. These deep notches and this plait have long been known and approved. My invention provides for making them with little labor and great perfection. I set two of the pins J' near together near the lower end and two wider apart near the upper end of the path along which the plait is 85 to extend. These pins serve the double function of holding the blanks laterally and also indicating by the holes t' t² t³ t⁴, which they produce, the edges of the portion which is to form the plait. I also employ another mode 90 of indicating the margins of such plaits. This is done by providing means for easily and correctly tracing two marks on the blanks T T' along the lines of each fold for this plait in the same manner as the line for one of the 95 seams is marked in the previously-described form of the apparatus. While the top plate J is in position on the blank I not only wet and fold the overhanging edges for the several infolds T', but also press on the pair of 100 blanks along the slots k' k² by means of a dull knife or analogous marker drawn along each slot, and thus mark on each blank. After I have lifted off the top plate K and the 105 pair of completed back pieces T T', with their holes and marks, the folding along the lines required to form the proper tapering plait T² is made by any convenient means, as simply operating with the fingers, and it is easy by the aid of these holes and marks to effect this 110 in exactly the right position.

In treating all forms of pieces the main plate instead of having a hard-metal surface may be faced on the upper side with a soft material, as blotting-paper or velvet, or both. 115 Such would allow the dull knife or other marking-tool, by sinking somewhat into the soft material, to more distinctly mark both fabrics. I can use hard material and slightly groove along the lines to be marked. I have 120 succeeded well with a hard plane surface, the marking by moderate pressure with a hard-metal tool being sufficiently visible after the goods have been allowed to lie several days. It is not common to have a delay in 125 the treatment of more than a few minutes, thus effecting the sewing while the folding is 130

fresh and while the edges are still damp and the remainder of the piece retains the greater stiffness due to its dry condition.

- Some of the advantages due to certain features of the invention may be separately enumerated, as follows: First, by reason of the fact that the lower plate A has the form and dimensions to aid the operator to place a pair of previously-shaped blanks of fabric thereon with a coinciding edge of each overhanging and of the combination therewith of the middle plate B, having its edge held just sufficiently within the edge of the bottom plate to allow the line of stitches to be located on the fabrics by its aid, and of the top plate C, having its edge coinciding with that of the bottom plate A, and of the pins J' in the bottom plate extending upward through the blanks and also through apertures in the plates, so as to engage both the plates and the pair of blanks of fabric and hold them against relative displacement laterally, I am able to correctly and smoothly fold the protruding edges of the fabrics one downward under the lower plate and the other upward over the upper plate and also to mark the position of the seam on each blank without requiring labor or skill; second, by reason of the fact that in addition to the above-recited qualities the top plate has slots in which the pins are received arranged to give liberty to move the top plate horizontally forward before it is lifted I am able to partially withdraw the top plate, and thereby present only a narrower portion thereof to be lifted from the fabric, and thus to better preserve and make permanent the folded condition of the upper blank of fabric. I do not in this patent claim the apparatus for locating the folds for producing the plaits nor the method of operating, such being made the subjects of separate applications for patent, as follows: one filed December 10, 1900, patent issued April 23, 1901, No. 672,487, and

another filed December 10, 1900, Serial No. 39,291, allowed July 18, 1902.

45

I claim as my invention—

1. As an apparatus for folding and marking portions of garments, a bottom plate having a finished edge and a clear space below, in combination with a removable middle plate to aid in marking the location of the seam and also with a removable top plate, and means for holding such plates and a pair of blanks of fabric against relative displacement laterally, all arranged to serve substantially as herein specified.

2. As an apparatus for folding and marking portions of garments a plate having the form and dimensions to shape an edge of the finished piece, adapted to support a fabric and carried on a support A² which provides a clear space under an edge portion of the plate to allow the infold portion of the blank to be folded downward and having pins set in such plates, in combination with a smaller plate having apertures arranged to receive said pins so as to resist displacement either of the fabric or of the plate and to allow the blank to be marked along the edge of the latter, and with a removable top plate having the form of the bottom plate and apertures arranged to receive said pins and allow the infold of the upper blank to be folded upward along such edge, said apertures in such top plate C being elongated to allow the plate to be held reliably against lateral displacement while in use and to be shifted longitudinally before removing, all substantially as herein specified.

In testimony that I claim the invention above set forth I affix my signature in presence of two witnesses.

PATRICK J. MENAHAN.
